UNITED STATES PATENT OFFICE.

THOMAS McGREGOR SIBBALD, OF TORONTO, ONTARIO, CANADA.

CASH-REGISTER.

1,083,035.

Specification of Letters Patent. Patented Dec. 30, 1913.

Application filed September 7, 1912. Serial No. 719,248.

To all whom it may concern:

Be it known that I, THOMAS McGREGOR SIBBALD, a subject of the King of Great Britain, and resident of the city of Toronto, 5 Ontario, Canada, have invented certain new and useful Improvements in Cash-Registers, of which the following is a specification.

The invention relates to improvements in 10 recording cash tills, as described in the present specification, and illustrated in the accompanying drawings that form part of the same.

The invention consists essentially of the 15 novel arrangement and construction of parts, whereby a plurality of plungers deliver coins of the different denominations to corresponding compartments in the till and coincidentally record each entry thereof.

20 The objects of the invention are to devise a till of simple and inexpensive construction particularly adapted for receiving the receipts of small purchases made in coin, whereby the same may be deposited in the till by the purchaser and a complete record 25 kept of all amounts received without the use of ink, type or other complicated attachment.

In the drawings, Figure 1 is a sectional 30 perspective view of a counter, showing the till arranged therein. Fig. 2 is a longitudinal sectional view of the counter and till. Fig. 3 is a cross sectional view of the counter and till. Fig. 4 is a sectional perspective view of the counter with the till removed, showing a detail view of the recording mechanism. Fig. 5 is a perspective detail view of the plunger. Fig. 6 is a perspective view of the bracket supporting the 40 ratchet.

Like numerals of reference indicate corresponding parts in each figure.

Referring to the drawings, 1 is a counter or other stand on which it is desired to support the till, though it must be understood that in the present specification, the invention is shown as applied to a counter such as used in bars, whereby the receiving portion of the till as hereinbefore described may 50 be placed level with the surface of the counter in order that the coins may be readily deposited.

2 is an opening in the top of the counter, having the bottom 3 and sides 4, and adapted to contain the till and receiving mechanism as hereinafter described.

5 are grooves made in the sides 4 adjacent to the top thereof.

6 is the receiving drawer of the till sliding into the opening 2 on the bottom thereof, and having compartments arranged therein by the partitions 7 as customary in cash receiving drawers.

8 is the plunger casing comprising the top, and bottom plates 9 and 10 respectively, the front strip 11 and the back strip 12, said front and back strips spacing the plates 9 and 10 one from the other to receive the plungers. The plunger casing 8 fits over the opening 2, and extends into the groove 5, thereby forming a sliding top for said opening level with the top of the counter proper.

13 are openings through the front plate 11.

14 are slots through the bottom plate 10, and in alignment with the opening 13.

15 are orifices through the top plate 9 graduated to the different sized coins.

16 are orifices through the bottom plate 10 corresponding in number and size with the orifices 15 through the top plate.

17 are plungers slidably arranged between the plates 9 and 10, and having the downwardly offset inner ends 18 terminating in the needle points 19, and extending through the slots 14. The plungers 17 at the outer ends thereof project through the openings 13, and have the buttons 20 secured thereto.

21 are orifices through the plungers 17 intermediate of the length thereof.

42 are bracket arms extending downwardly from the bottom plate 10.

43 are spiral springs hooked between the downwardly extending ends 18 of the plungers and the bracket arms 22, and normally holding each plunger to its outward position with the button some distance from the front plate 11, and the orifice 21 thereof directly beneath an orifice 15 in the top plate, the offset inner end 18 of the plunger abutting one end of the slot 14.

To make the payment of a purchase the purchaser places coins in the different orifices 15 according to the denomination indicated, and the salesman or receiving clerk on the inside of the counter pushes the button of the plunger in which the coin has been placed, and the coin is thus carried in the orifice 21 of the plunger between the top and bottom plates of the plunger casing until the coin is directly over the orifice 16.

through which it falls to the proper compartment in the till.

In order to record the number of coins paid into the till and their denomination a roll of paper is arranged to be punched by the needle ends of the plungers as herein-after described.

22 is a back board arranged to slide vertically into the back of the opening 2 in the counter top.

23 and 24 are roller brackets secured to the back board 22 at each end thereof.

25 is a pin rotatably mounted in one of the brackets 24, and having the squared inner end 26 and the ratchet 27 fixedly mounted on the outer end thereof.

28 are pins extending inwardly from the remaining of the brackets 23 and 24, the brackets at the end of the board opposite the ratchet being made of spring metal, whereby they may be sprung outwardly to receive the rollers 29 and 30, said rollers having recesses in the ends thereof to receive the pins extending from the brackets, 25 with one recess squared to fit the squared inner end 26 of the pin 25.

31 is a roll of paper wound about the roller 29, and threaded therefrom onto the roller 30.

32 is a bar secured to the back board 22, and extending therealong immediately behind the paper 31, and between the rolls 29 and 30.

33 are orifices at intervals throughout the length of the bar 32, and arranged opposite the needle points 19 of the plunger 17.

34 is a trip rod journaled at each end thereof in the brackets 35 secured at each side of the opening 2 toward the back thereof.

36 are trip arms secured to the trip rod 34 at intervals throughout the length thereof, and extending upwardly therefrom, and having the laterally turned end 37 passing 45 immediately behind the downwardly turned ends 18 of the plungers 17.

38 is a pawl secured to one of the trip arms 36, and engaging with the teeth of the ratchet wheel 25.

39 is a spiral spring having one end thereof secured to the trip arm carrying the pawl, and the other end thereof secured to one side 4 of the opening 2, whereby the trip arms are normally held to contact with 55 the downwardly turned inner ends of the plungers.

40 is a bell arranged in any convenient place toward the back of the opening 2.

41 is a striker secured to the trip rod 34, 60 and arranged to contact with the bell 40 each time the trip arms are actuated by the plungers.

Each time a plunger is moved inwardly to carry a coin into the till as hereinbefore

explained, the needle point at the inner end 65 of the plunger will pass through the paper, and into one of the orifices 33 in the bar 32, said bar 32 supporting the paper while being punctured. Coincident with the piercing of the paper the plunger moves the upper end 70 of one of the trip arms 36 inwardly, thereby rocking the trip rod 34, and moving the pawl 38 inwardly past the ratchet 25, and it may be here explained that the pawl is counter-weighted whereby it is continually 75 held in contact with the ratchet, and is further of sufficient length to allow the tooth thereof to pass beyond the ratchet a sufficient distance to allow the needle end of the plunger to pierce the paper and withdraw therefrom before the spring 39 has returned the trip arm a sufficient distance for the tooth of the pawl to engage with the ratchet and move the same one tooth, thereby 80 rotating the roll 30, and moving the paper a sufficient distance to receive another pierce. In this manner each movement of the plunger to deposit a coin in the till registers on the roll of paper opposite the denomination of the coin deposited, and the 85 back board 22 with the paper thereon may be readily removed from the opening 2 by drawing the plunger casing 8 outwardly a slight distance, and the number of punctures in the paper may be readily counted, the 90 different rows appearing thereon signifying the different denominations of coin. It will be thus understood that a complete record of all cash received will be kept, and it will be thus necessary for the salesman or receiving clerk to be certain that a coin of the proper value is recorded by each plunger, and as the purchaser deposits the money it is absolutely necessary for the receiving 95 clerk to operate the plunger or plungers necessary to deposit the amount of the purchase.

Many modifications may be made in the details of construction without departing from the spirit of my invention, and I do not wish the same to be confined to the exact form shown in the accompanying drawings.

What I claim as my invention is:

In combination, a coin receiving drawer, a plunger casing arranged above said drawer and comprising upper and lower plates having a series of orifices arranged therethrough in pairs the one of each pair being out of register with the other, a plurality of plungers reciprocatorily arranged between said casing plates and each having an orifice therethrough adapted to register successively with the orifices of each pair in said plates and having pointed inner ends, a pair of rolls rotatably mounted adjacent 120 said plunger casing and carrying a strip of paper, a ratchet secured to one of said rolls, a trip rod journaled adjacent said rolls, a pair of trip arms secured to the trip rod, 125 and a pawl secured to one of the trip arms, the pawl being arranged to engage with the ratchet.

springheld trip arms secured to said trip rod and adapted to be engaged by said plungers, a pawl carried by one of said trip arms and engaging with said ratchet, a 5 platen bar supported between said rolls and having a series of orifices therethrough over which said strip of paper passes and into which the pointed inner ends of said plun-

gers extend upon the reciprocation of the same.

Signed at city of Toronto, Canada, this 10 eighth day of July 1912.

THOMAS McGREGOR SIBBALD.
